UNITED STATES PATENT OFFICE.

LLOYD DRAEGER, OF MILWAUKEE, WISCONSIN.

CLIP OR HOLDER FOR LEAD-PENCILS, FOUNTAIN-PENS, OR SIMILAR ARTICLES.

1,162,732.

Specification of Letters Patent. Patented Nov. 30, 1915.

Application filed June 9, 1915. Serial No. 33,004.

To all whom it may concern:

Be it known that I, LLOYD DRAEGER, a citizen of the United States, residing at Milwaukee, in the county of Milwaukee and State of Wisconsin, have invented a new and useful Clip or Holder for Lead-Pencils, Fountain-Pens, or Similar Articles, of which the following is a specification.

My invention relates to clips or holders for lead pencils or similar articles, and the objects of my invention are, to secure the pencil or similar article to the clothing of the wearer so that the article will not be lost, to protect the clothing of the wearer from the lead of the pencil and at the same time protect the point of the pencil from being dulled by wear against the clothing, to provide a clip or holder that may be readily attached to the clothing at any convenient place, thus avoiding the necessity of pockets in light summer clothing and in the garments of women, to provide for ready detachability from the clothing, and other features and advantages of the device which will appear from the detailed description. I attain these objects by the device illustrated in the accompanying drawing in which,

Figure 1 shows the entire device. Fig. 2 shows the device partly constructed to illustrate the mode of making the same. Fig. 3 shows a longitudinal section through the device.

The clip is, in effect, a small tube formed entirely of one piece of wire wound in a close spiral. The taper portion *a* at the bottom of the clip is of the requisite length to receive the pointed end of the pencil. The curved portion *b* of the tube forms a spring clip to seize and hold the pencil from falling out when the wearer engages in any kind of work or exercise. At the upper end of the tube two turns or convolutions *C* of the wire are loosely wound outside of the tube and the end of the wire *d* is pointed as shown. To attach the device to the clothing, the point *d* is passed through the cloth and the tube is given a partial turn which forces the point *d* again through the cloth.

If it is desired to attach the holder still more securely to the clothing, the holder may be given an additional complete turn again forcing the point *d* twice through the cloth when the holder will be attached by both the convolutions *C* passing through the cloth. This attachment to the clothing may be made inside of a vest or coat pocket, but the holder is just as easily attached at any convenient place on clothing where no pocket is available.

As shown in Fig. 2, the entire device is formed of a single piece of wire. This wire is wound on a forming pin of the form which it is desired to give to the inside of the tube.

Fig. 3 shows in section how the curved portions *b* holds the pencil or other contained article. The pencil is marked *e*, and when passed through the curved part *b* it springs one convolution *f* to the left until it is in line with the next convolution on either side of it. Thus the interior of the tube may be considerably larger than the article it holds so that the article is very easily inserted in the holder.

This holder is so flexible it cannot possibly hurt the wearer. While intended primarily as a pencil holder, many other uses may be found for it, as for instance carrying a bunch of violets or other flowers, in which case it is very desirable to protect white or light colored clothing from the flower stems.

Having now fully described my invention, what I claim is—

1. A holder or clip for carrying a pencil or like article, consisting of a tube like receptacle having a substantially straight axis of figure, formed of a single piece of wire wound in continuous spiral convolutions, the last one or more convolutions being wound outside of the receptacle with a reverse lead to constitute an attaching device, and a plurality of convolutions intermediate the ends of the receptacle being wound on an axis offset from the axis of the receptacle.

2. A holder or clip for carrying and protecting a pencil or like article consisting of

a tube like receptacle formed of a single piece of wire wound in continuous spiral convolutions, said convolutions decreasing in diameter until the receptacle is closed at one end, wound with a reverse lead outside of the receptacle at the other end to constitute an attaching device, and a plurality of con-

volutions intermediate the ends being wound on an axis offset from the axis of the receptacle.

LLOYD DRAEGER.
